WILLIAM RUGER, JR., OF JANEVILLE, WISCONSIN, ASSIGNOR TO UNDERWOOD TYPEWRITER COMPANY, OF NEW YORK, N. Y., A CORPORATION OF NEW JERSEY.

CLUTCH FOR TYPE-WRITER PLATENS.

No. 849,751.

Specification of Letters Patent.

Patented April 9, 1907.

Application filed August 16, 1905. Serial No. 274,260.

To all whom it may concern:

Be it known that I, WILLIAM RUGER, Jr., a citizen of the United States, residing in Janesville, in the county of Rock and State 5 of Wisconsin, have invented certain new and useful Improvements in Clutches for Type-Writer Platens, of which the following is a specification.

This invention relates to the revoluble 10 platens of type-writing machines; and its object is to provide a simple, inexpensive, efficient, and durable mechanism for releasing the platen at will from the line-space ratchet-wheel so as to permit the platen to be rotated independently of said wheel for writing upon ruled lines or at intervals different from the usual line-space intervals.

In carrying out my invention I employ a band clutch or strap which is passed around 20 the platen-axle to frictionally engage the same, and I mount upon the line-space wheel a lever for tightening the strap, whereby both line-space wheel and platen are forced to rotate together. The lever may be moved 25 so as to release the strap or band, permitting the platen to be turned to any desired point, while the line-space wheel remains stationary.

In the accompanying drawings, Figure 1 is 30 a sectional plan of a portion of the platen and appurtenances of an "Underwood" type-writing machine, showing my improvements applied thereto, the clutch being shown closed, so that the platen and line-space 35 wheel must rotate together. Fig. 2 is a view, on a larger scale of details of the clutch mechanism, the clutch being shown closed. Fig. 3 is a sectional view of the parts seen at Fig. 2, the clutch being shown in full lines as 40 closed and dotted lines as released. Fig. 4 is a perspective view of the parts seen at Figs. 2 and 3. Fig. 5 is a plan view of the parts seen at Fig. 1.

The platen 1 is fixed upon an axle 2, which 45 is journaled in a boss 3, the latter mounted in a platen-frame, one end or side of which is seen at 4. Upon the extreme end of the axle is secured a hand-wheel 5 by means of a hollow hub 6 and a set-screw 7. By means of 50 this hand-wheel the platen may be rotated at any time in either direction.

Loose upon the platen-axle is a line-space wheel 8, having a hub 9. Said wheel is re-

leasably connected to the platen by means of a band-brake or friction-strap 10, which is 55 illustrated as endless and as surrounding the axle 2 at a point between the line-space wheel and the hand-wheel 5, so as to frictionally engage said axle, although it will be understood that a larger cylindrical surface 60 or collar may be provided for engagement by the band within the scope of the invention. The portion of the platen-axle encircled by the band may be regarded as a pulley.

The band is tightened, and therefore 65 caused to grip the axle, by means of a lever 11, which works upon a pivot-pin 12, eccentric to the platen-axle, and has a short arm or heel 13 within said band 10. Said arm 13 is effective to draw the band taut when 70 the lever is swung to the full-line position at Figs. 3 and 4, so that in order to release the platen it is only necessary to throw said lever to the dotted-line position at Fig. 3.

The lever-pin 12 is supported at one end 75 in the hub 9 of the ratchet-wheel and at its other end in a collar 14, loose upon the axle 2, but rigidly connected to said hub 9 by means of a pair of cleats 15, the latter secured by screws 16 or otherwise at its ends 80 to said hub and collar, so that the latter may be regarded as forming a portion of the hub of the line-space wheel. It is obvious that a stop 17 may be provided upon the lever to arrest the same when the arm 13 is in the 85 dead-center position, (shown in full lines at Fig. 3,) this being the time when the band is drawn tightest.

It will be seen that the lever, although revoluble bodily together with the line-space 90 wheel about the platen-axle, may be readily reached and operated at any point in the rotation of the line-space wheel and that the parts are compact and simple and not liable to get out of order, besides inexpensive to 95 manufacture and readily applicable to existing machines.

Having thus described my invention, I claim—

1. In a type-writing machine, the combination with a revoluble platen; a line-space wheel and an intervening endless-band brake, of a lever for tightening said band-brake, said lever and band-brake being so related that when the lever is upon dead-center, 105 the band is taut; and a stop for arresting the

2
band-tightening movement of said lever when the latter is about on dead-center.

2. In a type-writing machine, the combination with a revoluble platen, of a line-space wheel, a band-pulley connected to one of said elements, an endless brake-band encircling said pulley, and means for tightening and loosening said band; said brake-band, line-space wheel tightening means being revoluble with said platen.

3. In a type-writing machine, the combination with a revoluble platen having an axle, of a line-space wheel loosely mounted upon said axle and having a hub, a lever mounted upon said hub eccentrically to the platen-axle, and a brake-band engaged by said lever and encircling said platen-axle; said lever, hub and brake-band revoluble with the platen and line-space wheel.

4. In a type-writing machine, the combination with a revoluble platen, a line-space wheel, and an intervening endless-band brake, a part being encircled by the brake-band to enable the latter to make a frictional connection between the line-space wheel and the platen, of a lever for tightening said band-brake, said lever and band-brake being so related that by a movement of the lever to its dead-center position the band is tightened; said band-brake and lever revoluble with said platen.

5. In a type-writing machine, the combination with a revoluble platen, a line-space wheel, and an intervening endless-band brake, of a lever for tightening said band-brake, said lever and band-brake being so related that by the movement of the lever to its dead-center position the band is tightened,

and a stop for arresting the band-tightening movement of said lever when the latter is about on dead-center; said band-brake, lever and stop revoluble with said platen.

6. In a type-writing machine, the combination of a platen fixed upon an axle, a hand-wheel fixed on the extreme end of the axle to rotate the platen at any time in either direction, a line-space wheel loose upon the axle, and endless-band brake surrounding said axle between the line-space wheel and the hand-wheel and frictionally engaging said axle, a lever pivoted eccentrically to the platen-axle and having a short arm within said band to draw the band taut or release the same, and means supporting said lever; said supporting means being directly connected to said line-space wheel.

7. In a type-writing machine, the combination of a platen fixed upon an axle, a hand-wheel fixed on the extreme end of the axle to rotate the platen at any time in either direction, a line-space wheel loose upon the axle, an endless-band brake surrounding said axle between the line-space wheel and the hand-wheel and frictionally engaging said axle, a lever pivoted eccentrically to the platen-axle and having a short arm within said band to draw the band taut or release the same, and means supporting said lever; said supporting means being directly connected to said line-space wheel, and means for arresting the lever when said short arm is in dead-center position and the band is drawn tighter.
